HAIR DRYER

James Teague, Jr., Glenview, and Victor A. Peterfil, Oak Park, Ill., assignors to Sunbeam Corporation, Chicago, Ill., a corporation of Illinois

Filed Feb. 20, 1967, Ser. No. 5,865

Term of patent 14 years

(Cl. D86—10)

Fig. 1.

Fig. 2.

Fig. 7.

Fig. 8.

Fig. 9.

FIG. 1 is a perspective view of a hair dryer showing our new design, in open condition and with the control in extended position;

FIG. 2 is a top plan view of the hair dryer in closed condition;

FIG. 3 is a side elevational view of the hair dryer in open condition, with the control in the recessed position;

FIG. 4 is a plan view, partly in section along the line 4—4 of FIG. 3;

FIG. 5 is a rear elevational view of the hair dryer in open condition;

FIG. 6 is a partial sectional view taken on line 6—6 of FIG. 5;

FIG. 7 is an elevational view of a hair dryer in closed condition showing another form of our new design, wherein the upper rim, dome and handle members have been modified;

FIG. 8 is a top plan view thereof; and,

FIG. 9 is a partial sectional view taken on line 9—9 of FIG. 8.

We claim:

The ornamental design for a hair dryer, as shown and described.
